Primary Examiner—Brian N. Vinson

[57] CLAIM

The ornamental design for a snap-in trim element for securing foil sheet wall insulation in a support frame assembly or the like, as shown and described.

DESCRIPTION

FIG. 1 is a top and rear perspective view of a snap-in trim element for securing foil sheet wall insulation in a support frame assembly or the like showing my new design;

FIG. 2 is a horizontal cross-sectional view thereof, taken along line 2—2 of FIG. 1; and

FIG. 3 is a front elevational view thereof.

The element is shown broken-away in the views to indicate indeterminate length.

FIG 1

FIG 2

FIG 3
